UNITED STATES PATENT OFFICE.

CLARENCE G. GRABE, OF WILKINSBURG BOROUGH, PENNSYLVANIA, ASSIGNOR OF THREE-NINTHS TO LEO A. PARISH, OF PORT ALLEGANY, PENNSYLVANIA, AND TWO-NINTHS TO KARL P. FUHRMANN, OF SAULT STE. MARIE, ONTARIO, CANADA.

MOVING-PICTURE MACHINE.

1,276,054.

Specification of Letters Patent. Patented Aug. 20, 1918.

Application filed March 20, 1917. Serial No. 155,966.

To all whom it may concern:

Be it known that I, CLARENCE G. GRABE, a citizen of the United States, and residing in the borough of Wilkinsburg, in the county 5 of Allegheny and State of Pennsylvania, have invented or discovered new and useful Improvements in Moving-Picture Machines, of which the following is a specification.

My invention relates to means employed 10 in winding and unwinding the film strips in moving picture machines, and consists in new and improved means for regulating the discharge of the film from the feed reel.

The particular application of my invention which I have in view is the provision 15 of improved and practical means for unwinding a coil of film from its center toward its periphery, whereby said film, after being coiled on the receiving reel in a machine, is ready again for use in the picture machine 20 without the preliminary rewinding now customary.

In the present practice after a film has 25 been passed through a projector in exhibiting the picture upon the screen, and before the film can be again exhibited, it must be rewound on another reel, so that the pictures will be presented in proper progression on the screen.

30 A number of attempts have been made to perfect mechanism for rendering this preliminary unwinding unnecessary, but none of these devices have gone into commercial use, and the practice of preliminary rewinding still prevails.

My present invention comprises means whereby in rewinding a picture film from a feed reel, the rotation of said reel is controlled by the resistance of the film to the 40 pulling action of the traction mechanism of the moving picture machine.

In the accompanying drawings, which are merely intended to illustrate a practical embodiment of my invention and not to limit 45 the scope of the same to the construction shown, Figure 1 is a side elevation showing my invention applied to a conventional moving picture projector wherein the film is unwound from the interior of the coil of 50 film; Fig. 2 is a diametric section of the feed reel taken along the line II—II in Fig. 8; Fig. 3 is a broken elevation of the feed reel driving pulley and its associated parts; Fig. 4 is a front elevation of the film guide dis-

mounted; Fig. 5 is a broken plan view of the 55 receiving reel with the film guide in place; Fig. 6 is a broken side elevation of the reel with the film guide removed; Fig. 7 is a similar view with the guide in place; Fig. 8 is a reversed side elevation of the feed reel 60 and its mounting; Fig. 9 is an edge view of the receiving reel looking in the direction of the arrow in Fig. 1, and Fig. 10 is an enlarged vertical section of the same taken along the line X—X in Fig. 1. 65

The following is a detailed description of the drawings.

A represents the frame of a moving picture projector provided with the usual driving sprockets and rolls which are not described in detail, as they form no part of my present invention. Power is applied to the mechanism in any usual manner, such as by hand crank 1 and driving shaft 2. B represents the film strip. 70

The frame is provided at its upper end with a supporting bracket 3 for the feed reel C and at its lower end with a bracket 4 for the receiving reel C'. 75

The receiving and feed reels are counter- 80 parts of each other, and when an empty reel has been used to receive a film, it may be mounted on the other end of the machine as a feed reel and the film taken therefrom for a second exposure of the pictures or the filled 85 reel may be laid aside ready for introduction into the projector when desired.

The construction of my reel is as follows:

5 is a face disk provided with an axial 90 opening 6 and the usual ventilating ports. 7 is a cylindrical hub member provided at one end with a radial flange 8 which is secured to the face of disk 5 concentric with the axial opening 6. 9 is a cylindrical sleeve slipped over the hub 7 and free to rotate 95 thereon. 10 is a circumferential flange on said sleeve to which is soldered or otherwise secured a partially cutaway disk 11 which is more clearly shown in Figs. 1 and 6.

The disk 11 is provided with pins 12, 100 which engage the inclined slots 13 in the angular feet 14 of the metal clips 15 which are secured to the inner surface of an expanding and contracting film drum 16. Said drum is of resilient metal in the form 105 of a longitudinally split cylinder.

The heads or outer ends of the clips 15 protrude and are hooked, so that when the

drum 16 is expanded, said feet engage and support a second face disk 17 similar to face disk 5 but with a larger axial opening, as shown.

- 5 The drum 16 is expanded and contracted by means of a toggle lever mechanism 18 which has its ends pivotally connected to said drum and the disk 11, respectively. When said drum is expanded, as shown in 10 Figs. 6 and 10, the disk 17 is held in place by the clips 15, but when said drum is contracted, said disk is released from the drum, as shown in Figs. 2 and 7.

- The disk 11 and with it the disk 17 may 15 be rotated in relation to the disk 5 or may be locked thereto to move in unison therewith by means of a sliding pin 19 which is normally held in engagement with a hole in the flange 8 by means of a helical spring 20. 20 Said pin may be disengaged from said hole by means of a rocking lever 21 one of whose ends is pivotally connected to the outer end of said pin and whose free end is in the path of the hub of the film guide to be later 25 described.

When the reel is being used as a receiving reel, the pin 19 seats in said hole and the drum 16 is expanded, locking the disk 17 in place. In such case the hub 7 is slipped 30 over the end of a shaft 22 journaled horizontally in the bracket 4, a key 23 on said shaft seating in a key seat 24 in the bore of said hub, and a forked plate 25, of the usual type, being slipped over the tangentially 35 grooved end of the shaft 22 to hold the reel from slipping off. The other end of said shaft, beyond the bracket 4, is provided with a rigidly mounted clutch member 26 which is adapted to have frictional contact 40 with a clutch face of a pulley 27 loose on the shaft, but held in resilient engagement with said clutch member 26 by means of a helical spring 28 coiled about the shaft between the pulley and a collar 29 fixed on 45 the end of the shaft. A belt 30 connects said pulley with the driving shaft 2 of the projector.

It is thus seen that the film passing 50 through the projector gate is wound upon the reel C, said reel being power rotated, but in such a manner that sufficient slip is provided to prevent an excess tension on the film B and to prevent injury to the film should the projector sprockets not feed the 55 film fast enough.

When the reel, with the film wound thereon, with the first part of the film in the center of the coil, is to be used as a feed reel it is first mounted in the following 60 scribed disk holder which locks the face disks 5 and 17 together.

D is a flat metal annulus of somewhat larger outer diameter than that of the disks 5 and 17, and provided with a plurality of 65 rigidly mounted and equally spaced pins 31,

each provided with a pair of disk grooves or seats 32 on their inner faces. The perimeters of the disks 5 and 17 are flattened, as at 33, so that when the reel is turned into the proper position, the reel may be inserted between the pins 31 and then rotated until the true circular edges of the said disks engage and are wedged in the seats 32. Thus the two disks are locked together to move in unison. 75

To hold the coil of the film, wound about the drum 16, concentric and to prevent sagging while the film is being unwound from the center, I provide an exterior supporting band 34 of spring metal formed of a plurality of overlapping segments. Similar ends of the segments are pivotally connected to the inner ends of links 35 whose outer ends are pivotally connected to a metal annulus or ring 36 which is mounted on edge 80 in a circumferential series of grooves or seats 37 in the outer surfaces of the pins 31. The ring 36 may be rotated in either direction. When turned clockwise into the positions shown in Fig. 8, the links 35 contact 85 with the pins 31 and are thrown toward a position radial of the reel, thus contracting the band 34, and confining and centering the film coil. When the ring 36 is rotated in the opposite direction, counterclockwise, the pins 90 encountered will throw said links toward a tangential position in relation to the reel and expand said band 34 until it seats in the recessed central portions of the pins 31, thus providing sufficient clearance for 95 the insertion of the reel into the disk holder. 100

After the reel has been inserted into the disk holder, the band 34 is contracted to center the film coils and is locked against accidental expansion by means of a pivoted latch 38 mounted on one of the pins 31 and 105 engaging the teeth 39 on the ring 36.

I will now proceed to describe the method of mounting the feed reel in the projector.

The bracket 3 is of yoke form provided with bearings 40 and 41 in horizontal alignment. 42 is a two diameter shaft, whose large end protrudes through and is journaled in the bearing 40 and whose reduced end protrudes through the bearing 41. 43 115 is a cylindrical shaft in which the reduced diameter of the shaft 42 is journaled, and which itself extends through and is journaled in the bearing 41. The end of the shaft 43 protruding into the yoke of the 120 bracket 3 is provided with a rigidly mounted male clutch member 44 which is adapted to frictionally engage a female clutch member formed on the adjacent face of a pulley 45 loose upon the shaft 42. Between the pulley 45 and the bearing 40, a collar 46 is keyed to slide on the shaft 42, and said collar is provided with a spur 47 which is adapted to seat in a corresponding notch 48 in the bearing 40, but when said shaft is turned in 125 130

the proper direction, said spur moves out of said notch and, by contact with the end face of the bearing, forces the pulley 45 into frictional engagement with the clutch member 44, thus imparting rotation from the pulley to the shaft 43. The pulley is operatively connected by means of a belt with the power shaft 2 of the projector. 49 is a helical spring wound around the shaft 42 and having one end connected to the bearing 40 and the other end to said shaft, whereby said spur is automatically returned to its recess and the engagement between the pulley and the clutch member prevented except when 10 the shaft 42 is turned in the proper direction, as will be later described. 40^a is a thrust bearing for the end of the shaft 42.

The other end of the shaft 42 is flattened to form a blade 50 which protrudes from the 20 end of the cylindrical shaft 43 and is pierced by a pin hole 51.

The end of the shaft 43 which protrudes outwardly from the bearing 41 is reduced in diameter forming a shoulder 52 and said 25 reduced portion is also provided with a fixed key 53.

The reel C, inserted in the disk holder, as described, is mounted in the projector by slipping the hub 7 over the reduced portion 30 of the shaft 43 until it contacts with the shoulder 52, the key seat 24 being occupied by the key 53 so that said hub will move in unison with said shaft.

The film guide E is next mounted in the 35 reel. Said guide comprises a strip of metal of sufficient width to carry the film bent to form a helical track 54 supported by radial spokes 55 on an axial cup hub 56 which is adapted to slip over the outer end of the 40 sleeve 9 and is locked to rotate with said sleeve by means of a pin 57 on said sleeve engaging a longitudinal slot 58 on said hub. The closed end of said hub is provided with a slot 59 through which the blade 50 on the 45 end of the shaft 42 extends. 60 is a locking pin inserted in the hole 51 to prevent the accidental dismounting of the guide from the reel. It is thus seen that the guide and drum turn with the shaft 42.

50 Both the drum 16 and the guide E have their faces over which the film passes dished or hollowed out in the center so that contact between said faces and the film is only along the perforated edges of the film and the pictures are preserved from injury.

The inner portion of the track 54 is provided with an attached guard plate 61 to hold the film flat on the track. The face of said guide is also dished to avoid contact 60 with the central portion of the film. The severed edge of the drum 16, over which the film is led to enter between the inner end of the track 54 and its guide plate, is provided with an anti-friction roller 62 and 65 the inner end of the track is provided with

a similar roller 63. The other severed end of the drum is upset, as shown at 64, to avoid wear on the film. The outer end of the track 54 is provided with lateral guiding flanges 65 to carry the film properly 70 off of the track. When the guide is in place its inner end extends into the interior of the drum 16 close up to the disk 5, the disk 11 being cut away to permit the inward insertion of the guide into place. The helical 75 curve of the guide track carries the film outside of the plane of the reel and directs it downwardly into the plane of the projector mechanism.

When the guide is in place, its hub contacts with the free end of the rocking lever 21, thus drawing the pin 19 out of engagement with the hole in the hub flange 8, thus permitting the drum 16 and guide E to turn 80 independently of the disk 5.

When the reel C is mounted in the disk holder, the centering band 34 contracted to confine the film roll, the reel mounted on the shaft 43, and the guide E mounted in place, the drum 16 is contracted to loosen the inner 90 coils of film, and the inner end of the film is led over the rollers 62 and 63 and over the track 54, down through the projector mechanism and onto the receiving reel C'. The feed reel C is given a few turns to provide 95 sufficient slack in the film for this purpose.

The motion picture machine is now started by rotating the crank 1, whereby the receiving reel and the pulley 45 of the feed reel are rotated. The pulley 45 is theoretically rotated at constant speed, and the film is pulled by the projector sprockets over the drum 16 and out through the guide E. The effect of this pull is to tighten the film 100 against the drum and guide so long as the film coil in the feed reel and its supporting parts remain stationary or revolve at too slow a speed to keep the film moving freely over the drum and guide. The tightening of the film resulting from its frictional resistance to the surface of the drum and guide causes said guide and drum to turn for a short distance on the hub 7, with the result that the shaft 42 is turned in unison 105 therewith, thus rotating the collar 46 and moving the spur 47 out of engagement with the notch 48. This results in moving the collar in the direction of the pulley 45 and bringing the clutch member of said pulley 110 into frictional engagement with clutch member 44 and thus causing the disks 5 and 17 and with them the film coil to revolve. The result is the relief of the frictional resistance between the film and the drum and guide, owing to the formation of slack in the film 115 about the drum. The resistance of the film in its passage over the drum and guide being reduced, the spring 49 returns the guide and drum, the shaft 42 and the spur 47 into their normal position, thus relieving the frictional 120

125

The inner portion of the track 54 is provided with an attached guard plate 61 to hold the film flat on the track. The face of said guide is also dished to avoid contact 60 with the central portion of the film. The severed edge of the drum 16, over which the film is led to enter between the inner end of the track 54 and its guide plate, is provided with an anti-friction roller 62 and 65 the inner end of the track is provided with

engagement between the clutch members and releasing the drive from the film coil. It is evident that when frictional resistance increases between the film and the drum and 5 guide, the film coil is automatically speeded up to reduce such resistance, the rotation of the film coil being controlled by the resistance between the film and the drum and guide.

10 Thus the film is drawn from the interior of the film coil with a minimum of resistance or tension, thereby preventing injury to the film, as the film coil is automatically rotated at the just proper rate to feed the 15 film freely through the delivery mechanism.

In case the pull exerted by the projector sprockets upon the film is interrupted, the clutch mechanism between the pulley 45 and the shaft 43 remains inoperative and the 20 film coil remains stationary.

When the film is exhausted, the reel C may be removed from the shaft 43, the drum 16 expanded to engage and hold in place the face disk 17, the disk holder and the guide 25 removed, and the reel is ready to be inserted in the lower portion of the machine to receive another film. If desired the reel C' may be inserted in a disk holder, the guide put in place and the whole mounted on the 30 shaft 43, whereupon the process just described of running the film through the projector may be repeated.

It is evident from the foregoing that no 35 injury results to the film from my improved mechanism and much time and labor is saved in exhibiting films, no rewinding apparatus being required.

Although, for the sake of clearness, I have minutely described the embodiment of my 40 invention illustrated in the drawings, I do not wish to limit myself thereby, but claim broadly.

1. In a motion picture film reel, a film coil carrier, power-means for rotating said 45 carrier, a film guide mounted axially of said carrier and extending beyond the vertical plane of the latter in the form of a helical curve, whereby the film is led out of the interior of the film coil on said carrier to the 50 traction devices of the machine, and means whereby the pull of the film on said guide operatively connects said carrier and said power-means, for the purpose described.

2. In a motion picture film reel, a film coil 55 carrier, power-means for rotating said carrier, a split drum mounted axially of said carrier, a film guide extending out from the interior of said drum in the form of a helical curve, whereby the film is led out of the 60 interior of the film coil on said carrier to the traction devices of the machine, said drum and carrier being capable of rotation in unison but independently of said carrier, and means whereby the rotation of said 65 drum and guide in response to the pull of

the film operatively connects said carrier and said power-means, for the purpose described.

3. In a motion picture machine, a film coil carrier, power-means for rotating said 70 carrier, a film lead-out guide mounted in the axis of said carrier and rotatable independently of the same, and means whereby the rotation of said guide in response to the pull of the film operatively connects said 75 carrier to said power-means, for the purpose described.

4. In a motion picture machine, a film coil carrier, power-means for rotating said 80 carrier, a film lead-out guide mounted in the axis of said carrier and rotatable independently thereof, means whereby the rotation of said guide in response to the pull of the film operatively connects said carrier and said power-means, and means for returning 85 said guide to its original position when said pull is relieved, for the purpose described.

5. In a motion picture machine, a film coil carrier, power-means for rotating said 90 carrier, a film lead-out guide mounted in the axis of said carrier and rotatable independently thereof, means whereby the rotation of said guide in response to the pull of the film operatively connects said carrier and said power-means, and means whereby the 95 relief of said pull disconnects said carrier from said power-means, for the purpose described.

6. In combination with the traction devices of a moving picture machine, a film coil carrier, a driven element adapted to rotate said carrier, a split drum mounted axially of said carrier, a helical guide adapted to lead the film from the interior of said drum to said traction devices, said 100 drum and guide rotating independently of said carrier, and means whereby the movement of said drum and guide controls the 105 operative connection between said carrier and said element.

7. In a moving picture film coil carrier, a pair of disks, means for locking said disks together, an expandable drum located axially of said disks, and means whereby when said drum is expanded it locks said disks together but when said drum is contracted said drum is free to rotate independently of said disks, for the purpose described.

8. In a moving picture film coil carrier, a pair of disks, means engaging the peripheries of said disks to hold the same together, an expandable split drum located axially of said disks, and means whereby when said drum is expanded it locks said disks together but when said drum is contracted it is free to rotate independently of said disks, for the purpose described.

9. In a moving picture film coil carrier, a pair of disks, a drum located axially of said disks, and means for locking said disks 130

rigidly together, said means being provided with seats which are engaged by the perimeters of said disks, for the purpose described.

- 5 10. In a moving picture film coil carrier, a pair of disks having flattened perimetral portions, locking means adapted to encircle the perimeters of said disks and into which said disks may be inserted when their flattened portions register with said means, and means whereby when said flattened portions are rotated out of registration with said locking means said disks are locked into rigid relationship, for the purpose described. 35
- 10 11. In a moving picture film coil carrier, a pair of disks having flattened perimetral portions, locking means adapted to encircle the perimeters of said disks and into which said disks may be inserted when turned with 40
- 20 their flattened portions registering with said locking means, said means being provided with locking grooves, and means whereby when said flattened portions are rotated out of registration with said means the curved 45
- 25 perimeters of said disks are wedged into engagement with said grooves, for the purpose described. 50
12. In a moving picture film coil carrier, a pair of disks having flattened perimetral portions, a support, and a plurality of pins 55

extending from said support and adapted to encircle said disks, said disks being freely insertible between said pins when said flattened portions are turned in registration with said pins, and said pins being provided with grooves which are engaged by the curved perimeters of said disks when the latter are partially rotated, whereby said disks may be locked stationary, for the purpose described. 60

13. In a moving picture machine, a film reel comprising a pair of face disks, an annular holder engaging the perimeters of said disks and adapted to lock them in rigid relationship, and an expansible centering ring surrounding the outside of the film coil and supported from said holder, for the purpose described. 45

14. In a moving picture machine, a film reel comprising a pair of face disks, a 50 holder engaging the perimeters of said disks to lock them into rigid relationship, an expansible centering ring surrounding the film coil on said reel and supported from said holder, and means for locking said ring in 55 its adjusted position, for the purpose described.

Signed at Pittsburgh, Pa., this 17th day of March, 1917.

CLARENCE G. GRABE.
